RAILWAY TRUCK BOLSTER ASSEMBLY

Fred H. Spenner, St. Louis, Mo., assignor to
Scullin Steel Co., St. Louis, Mo., a corporation
of Missouri

Application October 16, 1950, Serial No. 190,285

1 Claim. (Cl. 105—197)

1

This invention relates to railway car trucks and is particularly directed to improvements in car trucks which will provide superior lateral riding characteristics and tracking qualities of the truck.

This invention is an improvement over an invention described and claimed by me in an application for patent relating to car trucks, filed March 29, 1945 and bearing Ser. No. 585,553, which has matured into Patent No. 2,551,064.

An object of the present invention is to provide a car truck with means for improving the lateral riding and tracking qualities thereof in order to obtain improved running characteristics of the truck.

It is an object of the present invention to provide a railway car truck with positive snubbing means operative in both the lateral and vertical directions of bolster movement whereby to improve the riding characteristics thereof.

A further object of the present invention is found in the arrangement of spring means disposed between the bolster and the car truck side frame and positioned in a manner to obtain variable snubbing loads or pressures on suitable friction elements operating between the spring means and friction surfaces on the bolster and side frame.

A still further object hereof is to arrange spring means in accordance with the foregoing object and wherein the spring means is employed to obtain snubbing loads for each of the directions of movement between the bolster and the car truck side frame.

My present invention comprises a car truck assembly having side frame members provided with bolster openings defined in part by vertical columns having guideways in opposed relation in the bolster opening, and in the arrangement of a spring-supported bolster movable between the guideways and presenting friction surface means for the cooperation of friction elements which are spring urged against the bolster friction surfaces and cooperating friction surfaces in the guideways of the side frame. My invention is particularly concerned with the arrangement of the spring means having a reaction against a bolster surface and directed against the friction elements to produce components of force thereon which may be varied in magnitude.

Further objects of my invention will be hereinafter more particularly pointed out and described when considered in connection with the accompanying drawing.

In the drawing:

Fig. 1 is a longitudinal elevational view of a

2

typical railway car truck assembly embodying the features of my present invention.

Fig. 2 is an enlarged fragmentary and partly sectioned plan view of a side frame and bolster end construction, the view being taken at line 2—2 of Fig. 1.

Fig. 3 is an enlarged fragmentary sectional elevation taken transversely of the car truck side frame, as indicated at line 3—3 in Fig. 1.

Fig. 4 is a view similar to that of Fig. 3 wherein a modified construction is disclosed.

Referring to the several views of the drawing by suitable numerals of reference, the railway car truck assembly may be seen to comprise a side frame 10, a bolster 11, a bolster supporting spring group 12 and track engaging wheels 13 mounted on the side frame 10 at axle journal boxes 14.

The side frame 10 of Fig. 1 comprises a longitudinal compression member 15 and a spaced longitudinal tension member 16 interconnected with the compression member by means of vertical column members 17 which, with the tension and compression members, define a bolster opening 9 in the side frame 10. Each of the vertically directed column members 17 provides a vertically directed guideway 18 which, as disclosed in Fig. 2, is formed by inboard and outboard flanges 19 and 20 respectively. Each of these flanges 19 and 20, in the preferred form of my invention, is arranged in vertical parallel and spaced relation in the manner shown in connection with Fig. 3, there being suitable ribs for increasing the strength of the flanges to the extent desired. The guideways 18 defined by and between the respective inboard and outboard flanges are located in the upper portion of the bolster opening 9 for a purpose to appear.

The bolster member 11 is of the usual box-type construction, in which the end portion 22 thereof is suitably formed to be received in the bolster opening 9 for movement between the opposed guideways 18. Integral with the bolster end portion 22 are oppositely extending lugs 23 which are adapted to be received in the guideways 18 and are movable relative to the guideways in both a vertical and lateral direction. Since each of the bolster lugs 23 is identical in construction, a detailed description of one thereof will be deemed sufficient for purposes of the present disclosure.

The bolster lug 23 integrally formed on the end portion 22 of the bolster 11 is shown in detail in connection with Figs. 2 and 3. The lug 23 consists of a medial wall 24 arranged normal to the longitudinal axis of the bolster 11 and form-

ing a common inner wall for the oppositely directed lug pockets 25, each pocket being defined by top walls 26, outer side walls 27, bottom walls 28 and inner side walls 29. The wall 29 is shown as providing the integral connection between the lug 23 and the bolster end portion 22. Each lug pocket 25 is adapted to receive a friction element or shoe 30 which is square in cross-section and has a frictional or rubbing contact with the side, bottom and top walls of the lug pocket 25. Each friction element 30 has an outer wall 31 which is in frictional contact with a wear plate 32 carried by the flanges 19 and 20 of the guideways 18.

As I have pointed out previously, the object of my invention is to improve the riding and tracking qualities of a railway car truck. I have discovered that the best lateral riding and tracking qualities of a car truck are obtained by locating the spring means 33 for each of the friction elements 30 in an angularly related position so that there is produced components of forces on the friction elements 30 which provide positive lateral and vertical frictional snubbing pressure for cushioning lateral direct motion. This angled arrangement of spring means 33 furthermore prevents harmonic oscillation of the lateral springs. I obtain the angled mounting of spring means 33 by forming the medial wall 24 of each lug with spring seats in the zone of the oppositely directed laterally offset studs 35 and by forming the closed end wall 31 of each of the friction elements 30 with a spring seat having a similar stud 36 which is located in opposed relation with the medial wall stud 35 and at a laterally offset position to determine the proper or desired angled location of the axis of each of the spring means 33. It will be observed in Fig. 2, that each of the spring means 33 is directed at the same angle with respect to the longitudinal axis of the bolster 11, and that in Fig. 3 the spring means 33 are located in a common plane which includes the longitudinal plane of the bolster 11. Another way of describing this relation is to say that the spring means 33 are located in a horizontal plane which is normal to the vertical surfaces of the guideways 18.

In the operation of my bolster snubbing assembly, it will be appreciated that the angular position of each of the spring means 33 relative to the direction of movement of the friction means 30 produces a large or dominant force component between the guideway wear plates 32 and the end wall of the friction means 31. By so directing the longitudinal axis of each of the spring means 33, I am able to obtain a positive component of force between the friction means 30 and the top, side and bottom walls of the bolster lugs 23 so that there is developed a positive frictional snubbing pressure for the lateral movement of the bolster 11. Since the spring means 33 are also located in the longitudinal plane of the bolster 11, I am also able to obtain lateral cushioning of the bolster, which is similar to the cushioning effect produced by the bolster spring group.

It is obvious from a careful consideration of the construction of my bolster lugs 23 and the assembly therein of friction elements 30 and spring means 33, that I may provide variable force components between the top, bottom and side walls of the lug pockets 25 and the adjacent surfaces of friction elements 30 in accordance with load conditions to be imposed on the car truck. In other words, by changing the spring seat construction shown to alter the angular position of the spring means 33, I am able to change the snubbing pressure of the friction elements 30 for obtaining a predetermined or desired degree of lateral snubbing pressure relative to the bolster 11.

In the view of Fig. 4, I have disclosed a modified construction for the vertically directed guideways 18. In the modified disclosure, the inboard and outboard flanges 19 and 20 respectively are angularly related so that downward movement or displacement of the bolster end portion 22 relative to the side frame 10 will serve to compress the springs 33 for friction elements 30 and thereby increase the action of the springs and the component of force for snubbing vertical motion of the bolster in accordance with changes in the loading of the railway car. In other respects, the modified form of my invention is identical with the structure disclosed and described in connection with Figs. 2 and 3.

Having now described my invention in connection with a preferred embodiment thereof, and having indicated certain modifications, it should be understood that I deem it within the spirit of my invention to have all equivalent modifications and rearrangements thereof included within the scope of the claim hereafter appearing.

What I claim is:

A bolster assembly: comprising an elongated bolster end with top, bottom and side walls, lugs integral with said bolster side walls and projecting laterally outwardly therefrom, each lug having a pair of oppositely opening pockets separated by a medial wall, said medial wall having seats on its opposite faces; and friction means in each lug pocket including a shoe having flat faces in sliding engagement in said lug pocket and an exposed flat end face with a seat on the inner side thereof, and a spring for each of said friction shoes with its ends seated between said medial wall seat and inner side seat of the shoe end face, said seats for the ends of said spring being similarly located in the longitudinal plane of said bolster and spaced different distances from said bolster side wall.

FRED H. SPENNER.
